UNITED STATES PATENT OFFICE

172,110

QUILTED PLASTIC SHEET MATERIAL

Julius Rutrick, New York, N. Y.

Application August 28, 1952, Serial No. 21,220

Term of patent 3½ years

(Cl. D87—3)

To all whom it may concern:

Be it known that I, Julius Rutrick, a citizen of the United States, residing in the city of New York, residing in the city of New York, county of Bronx and State of New York, have invented a new, original, and ornamental Design for a Quilted Plastic Sheet Material, of which the following is a specification, reference being had to the accompanying drawing, forming part thereof.

Fig. 1 is a plan view of a quilted plastic sheet material showing my new design, and

Fig. 2 is a cross section taken on line 2—2 of Fig. 1.

I claim:

The ornamental design for a quilted plastic sheet material, as shown.
